FOOD CART

Ira A. Keeshin and Ronald J. Kruse, Cincinnati, Ohio, assignors to Federated Department Stores, Inc., Cincinnati, Ohio

Filed July 28, 1971, Ser. No. 167,088

Term of patent 14 years

Int. Cl. D12—02

U.S. Cl. D14—3 M

FIG. 2

FIG. 3

FIG. 4

FIG. 5

FIG. 1 is a front elevational view of a food cart illustrating our new design;

FIG. 2 is a rear elevational view of the food cart of FIG. 1 with the umbrella broken away;

FIG. 3 is a top view of the cart of FIG. 2;

FIG. 4 is a left side elevational view of the cart of FIG. 2;

FIG. 5 is a right side elevational view of the cart of FIG. 2; and

FIG. 6 is a bottom plan view of the cart of FIG. 2.

We claim:

The ornamental design for a food cart, substantially as shown and described.
